206,208

COMBINED MIRROR AND LIPSTICK HOLDER

Henry Ashenfarb, 3135 Johnson Ave., Riverdale, N.Y.

Filed June 8, 1965, Ser. No. 85,629

Term of patent 14 years

(Cl. D86—10)

FIG. 1

FIG. 2

FIG. 3

FIG. 4

FIG. 5

FIG. 1 is a front elevational view of a combined mirror and lipstick holder showing my new design;

FIG. 2 is a right side elevational view, the left side being substantially a mirror image thereof;

FIG. 3 is a top plan view thereof;

FIG. 4 is a bottom plan view thereof; and

FIG. 5 is a rear elevational view thereof.

The broken line showing of the lipstick in FIGS. 1 and 2 is for illustrative purposes only.

I claim:

The ornamental design for a combined mirror and lipstick holder, as shown and described.
